Albert J. Horton.

By Frank W. Hubbard
Attorney

UNITED STATES PATENT OFFICE.

ALBERT J. HORTON, OF NEW YORK, N. Y., ASSIGNOR TO THE CUTLER-HAMMER MFG. CO., OF MILWAUKEE, WISCONSIN, A CORPORATION OF WISCONSIN.

RESISTANCE.

Application filed July 28, 1920. Serial No. 399,602.

To all whom it may concern:

Be it known that I, ALBERT J. HORTON, a citizen of the United States, residing at New York, in the county of New York and State of New York, have invented new and useful Improvements in Resistances, of which the following is a full, clear, concise, and exact description, reference being had to the accompanying drawing, forming a part of this specification.

This invention relates to resistances, and more particularly, to resistances of the unit type.

The invention has among its objects to provide a resistance unit having improved terminal means, which is of simple, rugged and durable construction and which can be quickly and readily assembled without any especial skill.

A further object is to provide an improved resistance unit wherein the resistance wire is connected to the terminals without the use of solder and wherein such connection is protected against oxidation.

Various other objects and advantages will hereinafter appear.

The accompanying drawing illustrates an embodiment of the invention which will now be described, it being understood that the embodiment illustrated can be modified without departing from the scope of the appended claims.

In the drawing,

Fig. 1 is a side elevational view of a resistance unit embodying the invention, a portion at one end of the unit being broken away;

Fig. 2 is an end view of the resistance unit shown in Fig. 1;

Fig. 3 is a fragmentary view of one end of the resistance unit shown in Fig. 1; the covering of the unit being shown in section; and,

Fig. 4 is an end view of one of the terminals shown in Fig. 1, illustrating the manner of connecting resistance wire thereto.

The resistance unit illustrated includes a bored cylindrical base 1, of porcelain or other non-conductive material and a resistance wire 2 coiled around said base and connected to terminals on opposite ends thereof.

Each of the terminals comprises a pin 3 and a piece of braided copper wire 4 wound around said pin and encircling said base.

As shown in Fig. 4, pin 3 is arranged on one side of said base and the ends of the terminal wire 4 are twisted together on the opposite side of said base to tightly wrap said terminal wire around said base and to bind said pin thereto. As shown in Fig. 4, one end of the wire 4 extends beyond the other to provide a lead 5 for connecting the resistance unit in an electric circuit while pin 3 is arranged at substantially right angles to the axis of base 1 and has its ends extending outwardly from the portion thereof engaged by wire 4 to provide projecting prongs 6. The resistance wire 2 is connected to the terminal wire 4 by tightly belaying the same around pin 3. After the resistance wire is secured to pin 3 in this manner, the ends of the latter are bent against the sides of the base which operation still further binds the resistance wire 2 to the terminal wire 4. A cementitious covering 7 is applied to the insulating base, such covering extending out to the ends of said base to cover the connection between the resistance wire and the terminals.

It is apparent that the aforescribed terminal can be quickly and readily assembled and that intimate electrical connection between the resistance wire and terminal is insured. Also it is apparent that the cementitious covering protects the connection between the resistance wire and terminal from oxidation and also insures against loosening of such connection. Further it should be understood that the term "cementitious covering" is used in a broad sense to define enamel or other suitable insulating coverings.

What I claim as new and desire to secure by Letters Patent is:

1. A resistance unit comprising a base, a coil of resistance wire mounted thereon, terminal for said resistance wire surrounding said base and provided with projecting parts for connection of the resistance wire thereto, said resistance wire being wound around said projecting parts to secure the same to said terminals.

2. A resistance unit comprising a base, a coil of resistance wire mounted thereon, terminals for said resistance wire surrounding said base and provided with projecting parts for connection of the resistance wire thereto, said resistance wire being wound around

said parts and said parts being bent to prevent unwinding of said resistance wire thereon.

3. A resistance unit comprising a base, a coil of resistance wire mounted thereon, terminals for said unit each surrounding said base and provided with projecting prongs, said resistance wire being looped around said prongs to bind the same to said terminals.

4. A resistance unit comprising a base, a coil of resistance wire mounted thereon, terminals for said unit each surrounding said base and provided with projecting prongs, said resistance wire being wound around the prongs on said terminals to secure the same thereto and said prongs being bent to prevent unwinding of said resistance wire thereon.

5. A resistance unit comprising a base, a coil of resistance wire mounted thereon, terminal devices for said unit each including a pin and a conductive lead wound around said pin and encircling said base, said resistance wire being connected to said lead by belaying the same on said pin.

6. A resistance unit comprising a base, a coil of resistance wire mounted thereon, and terminal devices for said unit, each com-

prising a conductive lead surrounding said base and a belaying pin secured to said base by said lead, said resistance wire being belayed on said pin to connect the same to said conductive lead.

7. A resistance unit comprising a base, a coil of resistance wire mounted thereon and terminal devices for said unit each including a pin and a conductive lead surrounding said base, said lead being wound around said pin and having its ends twisted together to secure the same to said base, and said resistance wire being connected to said lead by belaying the same on said pin.

8. A resistance unit comprising a base, a coil of resistance wire mounted thereon, terminal devices for said unit each including a pin and a conductive lead surrounding said base and arranged to bind said pin thereto, said resistance wire being connected to said lead by belaying the same on said pin and a cementitious covering adhering to said base and enclosing said resistance wire and the connection between the same and said lead.

In witness whereof, I have hereunto subscribed my name.

ALBERT J. HORTON
